UNITED STATES PATENT OFFICE.

CHARLES D. OESTERLEIN, OF CINCINNATI, OHIO, ASSIGNOR TO THE OESTERLEIN MACHINE COMPANY, OF CINCINNATI, OHIO.

MILLING-MACHINE FEED MECHANISM.

1,138,010.

Specification of Letters Patent.

Patented May 4, 1915.

Application filed February 1, 1915. Serial No. 5,387.

To all whom it may concern:

Be it known that I, CHARLES D. OESTERLEIN, a citizen of the United States, residing at Cincinnati, Hamilton county, Ohio, have 5 invented certain new and useful Improvements in Milling-Machine Feed Mechanism, of which the following is a specification.

This invention, pertaining to milling machine feed mechanism, relates to a construction aiming at peculiarly convenient accessories enabling the operator to quickly change from a slow feed for the cutting operation to a fleeting advance in the direction of the cutting feed for passing parts of the 15 work which require no cutting, or to quickly change from the slow or quick movement of the work in the feeding direction to a fleeting return in the opposite direction.

The invention will be readily understood 20 from the following description taken in connection with the accompanying drawings in which:

Figure 1 is a side elevation of a milling machine fitted with my improved feed mechanism: Fig. 2 a side elevation of important parts of the feed mechanism, some of the parts appearing in vertical section in the plane of line *a* of Figs. 3 and 4: Fig. 3 a 25 plan of important parts of the feed mechanism, portions appearing in the plane of line *b* of Figs. 1, 2 and 4: Fig. 4 a rear elevation of the case inclosing parts of the improved feed mechanism: and Fig. 5 a rear side elevation of the clutch-shifting lever in conjunction with its throwing-plunger, the 30 housing of the throwing plunger appearing in vertical section in the plane of line *c* of Figs. 3 and 4.

In the drawings:—1, indicates the 40 columnar frame of a milling machine of well known type: 2, the arbor of the machine: 3, the knee mounted for vertical adjustment on the frame: 4, the saddle mounted for adjustment in and out on the knee: 5, the 45 work-holding table mounted for movement in the saddle in a direction at right angles to the axis of the arbor: 6, the feed-shaft carried by the knee and adjustable with it and serving to give motion to the mechanism 50 carried by the knee for giving feeding motion to the table relative to the frame and arbor, this shaft carrying one member of a universal joint: 7, a tumbling shaft connected by universal joint with shaft 6: 8 a 55 shaft journaled on the frame and having

universal joint connection with that end of tumbling shaft 7 opposite the end which is connected with shaft 6, shaft 7 being of telescopic character to compensate for the diverse vertical positions of the knee.

All of the above-mentioned parts are, or 60 may be, of usual construction and subject to usual modifications. Shaft 8, being driven by power, transmits motion to shaft 6 which, in turn, transmits motion to the feed mechanism carried by the knee to cause the work-holding table to move slowly in the feeding direction to advance the work to the cutter, reversing mechanism being interposed between shaft 6 and the feeding devices of the table so that the table may be caused to move in either direction, all as 65 used in this class of machines.

Proceeding with the drawings:—9, indicates a gear loose on shaft 8 and positively 70 driven at slow speed by some rotating part of the machine, the same as such gear is usually rotated when the gear is fast on shaft 8: 10, a clutch-hub on gear 9: 11, a sleeve loose on shaft 8: 12, a pulley fast on sleeve 11: 13, a clutch-hub or head on the inner end of sleeve 11, opposite the clutch-hub on gear 9, there being considerable space between the two clutch-hubs, and the 75 clutches of the two hubs facing in the same direction: 14, the clutch-member splined on shaft 8 and adapted to slide into engagement with either of the clutch-members 10 and 13: 15, a belt, driven from any suitable 80 source of power, preferably from some rotating part of the machine, and adapted to rotate pulley 12 at a much higher rate of speed than that of gear 9: 16, a shaft supported by the frame of the machine at right angles to shaft 8: 17, a clutch-fork fast on shaft 16 85 and engaging sliding clutch 14 and adapted, by oscillatory adjustment, to throw the clutch into engagement either with the clutch on gear 9 or with the clutch on sleeve 11: 18, an arm fast on shaft 16 and adapted, 90 by its oscillations, to give motion to the clutch-fork and shift the clutch: 19, a shaft journaled in the frame of the machine and extending across it from side to side: 20, a pair of treadles, one on each side of the machine, fast at their rear ends on shaft 19 and 95 extending forwardly below the level of the knee, near the base of the machine: 21, an arm fast on shaft 19 and projecting upwardly, its upper end being at substantially 100 105 110

the level of the lower end of arm 18: 22, a rod pivoted at its opposite end to arms 18 and 21, with lost motion at its connection with arm 18: 23, a fixed part of the machine frame, surrounding rod 22: 24, a spring surrounding rod 22 and normally under compression between fixed part 23 and a collar fast on the rod: 25, a casing secured to the outside of the frame of the machine and further 10 nishing bearings for shafts 8 and 16 and an inclosure for the clutch mechanism: 26, an arm projecting upwardly from arm 18 and provided at its upper end with a triangular tooth: 27, a vertically sliding spring-plunger 15 supported by the casing over arm 26 and having an angular tooth coöperating with the tooth on arm 26: and 28, the usual handle carried by the knee and serving as a means by which the reverse gearing of the 20 knee may be shifted when it is desired to change the direction of the feeding motion.

Looking at Fig. 1 the continuous rotation of shaft 8 causes the continuous rotation of shaft 6 and the feeding mechanism connected with the shaft 6, while the telescopic and universal-jointed character of shaft 7 permits of the transmission of motion from shaft 8 to the mechanism of the knee in any position of vertical adjustment of the knee, 25

30 the direction of motion of the feed of the table being determined by the reverse mechanism carried by the knee and controlled by handle 28, all as usual in milling machines of this general type. It will be understood 35 by those familiar with this type of milling machines, that it is customary in machines of this type to transmit the motion to shaft 8 through the medium of a so-called "speed-box" to permit of the rate of feed being adjusted, shaft 8, however, rotating constantly in one direction, whatever be its rate of speed, which rate of speed will always be a low rate appropriate to the feeding of the work to the cutter. If gear 9 were fast on 40 shaft 8 the above-mentioned usual performance of the feeding mechanism would be realized. In the present case, however, gear 9 is loose on shaft 8, spring 24 keeping the sliding clutch in normal engagement with 45 gear 9, the normal effect being therefore the same as if gear 9 were fast on shaft 8. The spring, in holding the clutch into normal engagement with gear 9 also holds the treadles in elevated position. If, now, it be desired 50 to give to the table a fleeting motion, it is only necessary to depress either treadle, which depression results in disengaging the sliding clutch from gear 9 and throwing it into engagement with the sleeve driven at 55 comparatively high speed by pulley 12, the clutch returning to condition for slow feed- 60

ing motion the instant the treadle is released. Spring 24 will, when permitted to the foot, act quick enough to instantly and completely throw the clutch from the abnormally fast to the normally slow clutch-member without there being any dwelling of the sliding clutch in idle neutral position, and without serious liability for the damaging of impartially engaged clutch teeth. The workman, in depressing the treadle to shift the clutch from the low to the high speed could, with proper energy and care, shift the clutch to the fast condition without incompletely engaging the clutch. But, if the workman fails in promptness or completion of action on the treadle, spring-plunger 27 will quickly and completely throw the clutch farther than his carelessly employed foot might do, the lost motion connection between rod 22 and lever 18 permitting this action, and the treadle, while depressed, serving to hold the sliding clutch in engagement with the clutch of the sleeve. Owing to the dual character of the treadle, which straddles the frame of the machine, the workman may operate the treadle with the foot best available in connection with his position at the machine.

I claim:—

Milling machine feed mechanism comprising, a vertically adjustable knee, a work-holding table mounted for movement thereon, a shaft journaled in the knee for giving traversing motion to the work-holding table, a fixed shaft journaled on the frame of the machine, a telescopic shaft connected to said knee shaft and fixed shaft by universal joints, a gear loose on said fixed shaft and adapted for continuous rotation, a pulley loose on said fixed shaft and adapted for rotation in the same direction as said gear but at higher speed, clutch-members connected with said gear and pulley, a clutch-member splined on said fixed shaft and adapted to lock either the gear or the pulley to the shaft, a clutch-throwing arm connected with said splined clutch-member and adapted for shifting that clutch-member, a treadle pivoted to the frame of the machine, a rod connecting said treadle with said clutch-throwing arm, and a spring acting between a fixed portion of the frame of the machine and said clutch-throwing arm and serving to normally hold the treadle in elevated position and the splined clutch in engagement with said gear, combined substantially as set forth.

CHARLES D. OESTERLEIN.
